UNITED STATES PATENT OFFICE.

JAY GORDON MITCHELL, OF CLEVELAND, OHIO, ASSIGNOR TO THE NORTH ELECTRIC COMPANY, OF CLEVELAND, OHIO, A CORPORATION OF OHIO.

TELEPHONE SYSTEM.

1,025,477.

Specification of Letters Patent.

Patented May 7, 1912.

Application filed August 8, 1908. Serial No. 447,583.

To all whom it may concern:

Be it known that I, JAY G. MITCHELL, a citizen of the United States, residing at Cleveland, in the county of Cuyahoga and State of Ohio, have invented certain new and useful Improvements in Telephone Systems, of which the following is a specification, reference being had therein to the accompanying drawing.

10 My invention relates to telephone systems, and especially to trunking circuits for the same.

It has for its object the provision of improved means for trunk signaling and for 15 supervising all trunk connections.

Briefly stated, my invention comprises a metallic circuit trunk line extending between an A operator and a B operator, provided at the B end with a pair of condensers, one in each limb, a signal magnet normally bridged across the trunk through the back contact of a cut-off relay, so as to include one of the condensers, and a supervisory relay having two windings, one permanently bridged around one condenser and the other bridged through the front contact of the cut-off relay around the other condenser; the cut-off relay having its circuit closed through the contacts of the trunk 25 plug when inserted in a jack by the B operator, and the supervisory relay controlling a signal device. The trunk signal in addition to its actuating winding has a second holding or locking winding, closed when it 30 is energized and controlled by a contact operated by a listening key and key for holding the trunk.

Other features of the invention will fully appear from the following description and 40 appended claims.

Referring to the accompanying drawings, Figure 1 shows a subscriber's station, an A operator's cord circuit, and the terminal of an outgoing trunk adapted to be connected through said cord circuit with a subscriber's line. Fig. 2 shows the circuits at the B end of the trunk, and a terminal of a subscriber's line similar to that in Fig. 1. Fig. 3 is a simplified diagram of the circuits of 45 Fig. 2.

Referring to Fig. 1, A is a subscriber's station with a line circuit 1-2 extending to the central office where it terminates on a jack J, and is provided with a line relay 50 L and a signal L' controlled thereby. This

circuit arrangement may be varied, as it forms no part of the present invention, and it will be noted that multiple jacks may be employed although they are not herein shown. A line circuit is adapted to be connected to other lines by means of the plugs P, P' connected by a cord circuit having listening and ringing keys Q, Q', and double wound bridged supervisory relays S, S' separated by condensers C, C', so that current from the main battery M will flow in both directions over the cord to the respective lines. J' is a trunk jack forming a terminal of an outgoing trunk to another switchboard or exchange. This has tip, ring and sleeve contacts to cooperate with the respective contacts of the plug P'.

Referring now to Fig. 2, the trunk conductors 3-4 extend to the B exchange, where they are connected through the contacts of the night service key D and the condensers C', C² to the plug P². A combined listening and ringing key Q², Q³ is provided in the trunk, also a key Q⁴ for holding connection of the trunk at central and a guard lamp q⁴ controlled by this key. The trunk calling signal is indicated at S² and the supervisory signal at S³. The calling signal is directly controlled through the trunk by means of its winding s' bridged from point 5 at the condenser C' through the normally closed back contact of the cut-off relay R to the point 6 at the condenser C². The holding winding s² is provided on the signal, closed when it is actuated, and controlled by contacts of the listening key Q² and the holding key Q⁴. The supervisory signal S³ is controlled by the double wound relay R', one of whose windings r is bridged from the point 7 at condenser C' to the point 5 on the other side of the same; while the other winding r' is similarly bridged when the relay R is energized, from the point 6 at condenser C² to the point 8 on the other side of the same. The circuit connections of these various pieces of apparatus, and their functions, will particularly appear from the following statement of operation:

Assuming that subscriber A has called for 105 connection with a subscriber in the branch or B exchange (as for example subscriber A' in Fig. 2), the A operator answers by inserting the plug P in the calling line jack, and having ascertained the number wanted, inserts 110

- the plug P' in the trunk jack, and rings out over the trunk. Current from her generator passes through the following circuit: trunk wire 3 to the contacts of key D (Fig. 2), 5 wire 9, winding s', wire 10, normally closed contact r², wire 11, point 6, through the condenser C², wire 12, contacts of key D, trunk wire 4 and back to the A exchange. This current energizes the signal S² whose mag- 10 net in pulling up its armature closes the following circuit of the winding s²: from the frame at 13 to the windings s², wire 14, closed contacts of key Q⁴, wire 15, closed contacts of key Q² and wire 16 to battery. 15 The signal remains displayed after the ringing ceases. The B operator uses the listening key Q² and ascertains the number wanted, breaking the circuit of the holding winding s² and restoring the signal S² at the same 20 time. She then inserts the plug P² in the wanted jack and by means of her ringing key Q³ sends out ringing current by the following path: generator G (indicated by letter only), key Q³, wire 16, closed contacts 25 of key D, wire 17 to the tip of the plug P² and subscriber's line back to the ring of the plug wire 18, closed contacts of the key D, wire 19 to the key Q³ and back to the generator. After the connection is complete 30 and the called subscriber has answer, the supervisory relay R' controlling the signal S³ is itself controlled over the following circuit: Current flows from the central office at the A end of the trunk over the trunk 35 wire 3, contacts of key D, wire 9, to the point 5, wire 20, to winding r of the supervisory relay, wire 21, to point 7, wire 22, closed contacts of key Q³, wire 16, closed contacts of key D, wire 17 to tip of the plug 40 and subscriber's line to station A' and back through the ring by wire 18, contacts of key D, wire 19, contacts of key Q³, wire 23, point 6, wire 11, contact r³ of relay R (which is closed as long as the plug P² is in the 45 line jack), wire 24, winding r' of relay R', wire 25, point 8, wire 12, closed contacts of key D, trunk wire 4 and back to the central office. As long as the called subscriber has his receiver off the hook and his line circuit 50 thereby closed, the relay R' pulls up, and maintains the circuit of the supervisory signal open, this circuit being as follows: from main battery M', wire 28, contact r⁴ of cut-off relay R, wire 29, contact r⁵ of relay R', wire 30, supervisory relay and back to battery. When the subscriber hangs up the contact r⁵ is closed and the supervisory signal is displayed. 55 The holding key Q⁴ when actuated closes 60 the circuit of the guard lamp q⁴ as follows: Main battery M', wire 31, key Q⁴, wire 32, lamp q⁴, wire 33 and back to battery. It also bridges across the trunk a coil H, which serves to maintain the trunk circuit closed 65 so far as the A operator is concerned, the

connections being as follows: Trunk wire 3, key D, wire 9, point 5, wire 34, coil H, wire 35, key Q⁴, wire 26, point 8, key D, trunk wire 4 and back to central office. The guard lamp q⁴ keeps the B operator advised 70 that the trunk is being held, and when the plug P² is withdrawn the cut-off relay R lets go and all the other parts are restored to normal.

Fig. 3 shows schematically the relation 75 of the parts without the complication of Fig. 2, all keys being omitted. The magnets and relays are marked the same as in Fig. 2 and further description thereof is deemed unnecessary.

It is obvious that many changes in detail 80 may be made in this circuit and in the apparatus employed therein without departing from the invention, and I wish it understood that all such changes are contemplated by 85 me as fairly fall within the scope of the appended claims.

Having thus described my invention what I claim and desire to secure by Letters Patent is—

1. A trunk signaling circuit for telephone exchanges, having a metallic circuit trunk line with a condenser at the B end in each limb and a supervisory relay having windings bridged around said condensers, together with a signal controlled by said relay, whereby current over the trunk line may pass through to a called subscriber's line for purposes of supervision. 95

2. A trunk signaling system for telephone exchanges comprising a metallic circuit trunk line deriving current from an A operator's cord circuit, a pair of condensers at the B end, one in each side of the trunk, and a supervisory relay having two windings, 100 each connected around one of the condensers, together with means at a subscriber's station for controlling the flow of current in his line and a signal controlled by said supervisory relay. 105

3. In a telephone exchange system, subscribers' lines, an A operator's position containing answering terminals for a plurality of lines, a B operator's position containing calling terminals for a plurality of lines, a 110 cord circuit at the A position adapted to cooperate with the line terminals, a trunk line extending from the A to the B position, condensers in opposite sides of the said trunk, and an advance signal connected from a point on the B side of one condenser to a point on the A side of the other, together with a source of periodic signaling current associated with the A operator's cord circuit, whereby said advance signal may be 115 actuated by the A operator, but will remain irresponsible to direct current flow in any portion of the trunk. 120

4. In a telephone exchange system, subscribers' lines, an A operator's position con- 125

taining answering terminals for a plurality of lines, a B operator's position containing calling terminals for a plurality of lines, a cord circuit at the A position adapted to cooperate with the line terminals, a trunk line extending from the A to the B position, a source of direct current and a supervisory signal responsive thereto connected with the cord circuit at the A position, a holding key 5 in the trunk at the B position, and means controlled in the actuation of said holding key to disable the A supervisory signal.

5. In a telephone exchange system, subscribers' lines, an A operator's position containing answering terminals for a plurality of lines, a B operator's position containing calling terminals for a plurality of lines, a cord circuit at the A position adapted to cooperate with the line terminals, a trunk line 10 extending from the A to the B position, a source of direct current and a supervisory signal responsive thereto connected with the cord circuit at the A position, a holding key 15 in the trunk at the B position, means controlled in the actuation of said holding key to disable the A supervisory signal, so as to hold the trunk, and a guard signal also controlled in the actuation of said key to indicate that the trunk is being held.

30 6. In a telephone exchange system, subscribers' lines, an A operator's position containing answering terminals for a plurality of lines, a B operator's position containing calling terminals for a plurality of lines, a cord circuit at the A position adapted to cooperate with the line terminals, a trunk line 35 extending from the A to the B position, a source of direct current and a supervisory signal at the A position responsive to the 40 current flow from said source in the cord and trunk when conjoined, a holding key in the trunk at the B position, and a short circuiting device adapted to be bridged across the trunk on the actuation of said key in 45 order to hold the trunk and prevent the effective display of said supervisory signal.

7. In a telephone exchange system, subscribers' lines, an A operator's position containing answering terminals for a plurality of lines, a B operator's position containing calling terminals for a plurality of lines, a cord circuit at the A position adapted to cooperate with the line terminals, a trunk line 50 extending from the A to the B position, a source of current and a supervisory signal at the A position responsive to current flow from said source in the cord and trunk when conjoined, a holding key in the trunk at the B position, and a coil adapted to be bridged 55 by said key across the trunk so as to short circuit the same and maintain the A supervisory signal undisplayed, thereby holding the trunk.

8. In a telephone exchange system, sub- 60 65

taining answering terminals for a plurality of lines, A B operator's position containing calling terminals for a plurality of lines, a cord circuit at the A position adapted to cooperate with the line terminals, a trunk line 70 extending from the A to the B position, a source of current and a supervisory signal at the A position responsive to current flow from said source in the cord and trunk when conjoined, a holding key in the trunk 75 at the B position, a coil adapted to be bridged by said key across the trunk so as to short circuit the same and maintain the A supervisory signal undisplayed, thereby holding the trunk, and a guard signal adapt- 80 ed to be displayed when the key is actuated, to show that the trunk is being held.

9. In a telephone exchange system, subscribers' lines, an A operator's position containing answering terminals for a plurality of lines, a B operator's position containing calling terminals for a plurality of lines, a cord circuit at the A position adapted to cooperate with the line terminals, a trunk line 85 extending from the A to the B position, a source of direct current and a supervisory signal 90 both associated with the A cord circuit, said signal being responsive to current flow from the source through the cord and the trunk when conjoined, and a supervisory signal at the B position connected to the trunk so as to maintain the balance thereof while taking current in series from the A source through the A supervisory signal and the called subscriber's line, whereby 95 simultaneous indications of the state of a connection are afforded at both A and B positions.

10. In a telephone exchange system, subscribers' lines, an A operator's position containing answering terminals for a plurality of lines, a B operator's position containing calling terminals for a plurality of lines, a cord circuit at the A position adapted to cooperate with the line terminals, a trunk line 105 extending from the A to the B position, a source of current and a supervisory signal responsive thereto in the A cord circuit, inductive means maintaining the continuity of the trunk at the B position, and a supervisory signal connected in shunt of said inductive means, whereby current supply for the called subscriber's line will pass from the A source through both the A and the B supervisory in series, with the consequent 110 simultaneous control of both by the called subscriber.

11. In a telephone exchange system, subscribers' lines, an A operator's position containing answering terminals for a plurality of lines, a B operator's position containing calling terminals for a plurality of lines, a cord circuit at the A position adapted to cooperate with the line terminals, a trunk line 125 extending from the A to the B position, a 130

ringing generator at the A position, a signal device at the B position responsive to current from said generator through the trunk, self-locking means adapted to maintain 5 said signal displayed after its initial actuation by said ringing current, and unlocking means for the same controlled by the B operator in the use of her listening key.

12. A telephone exchange system including 10 telephone lines extending from sub-stations to one exchange, telephone lines extending from sub-stations to a second exchange, a trunk circuit extending between said exchanges and having operator-controlled means at the first exchange for con- 15

necting it with telephone lines extending to the first exchange, link circuits at the second exchange for uniting lines extending thereto, clearing-out or supervisory signaling apparatus associated with said link circuits, and operator-controlled means at the first exchange for preventing the operation of said supervisory or clearing-out signaling apparatus at the second exchange. 20

In testimony whereof I affix my signature 25 in presence of two witnesses.

JAY GORDON MITCHELL.
